DRY POWDER FIRE EXTINGUISHER

Stewart Boal, Winnetka, Ill., assignor to Margate Corporation, Chicago, Ill., a corporation of Illinois

Application May 19, 1955, Serial No. 509,462

5 Claims. (Cl. 169—31)

This invention relates generally to fire extinguishers and more particularly, to portable fire extinguishers wherein a pressurized gas is used to propel a dry powder fire extinguishing medium onto the fire.

Many various constructions of fire extinguishers have been made in the past in which a pressurized gas is used to propel a dry powder fire extinguishing medium onto the fire. See, for example, U. S. Patent No. 2,580,448. All of these devices, however, have been large and unwieldy and, therefore, unsatisfactory for use as portable fire extinguishers and difficult to operate.

It is, therefore, an object of this invention to provide a fire extinguisher of the dry powder type that is relatively light, compact, and satisfactory for use as a portable fire extinguisher.

It is a further object of this invention to provide a portable fire extinguisher of the dry powder type which may be carried and operated by one hand.

It is a further object of this invention to provide a fire extinguisher of the dry powder type that has an integral and compact valve which is easy to manufacture and operate.

My invention comprises an integral valve housing attached to the receptacle which contains the pressurized gas and powder fire extinguishing medium. The housing encloses the outlet valve and a manually operated pilot valve. A chamber is provided within the valve housing containing a piston. The outlet valve is affixed to and actuated by the piston rod. A passageway leading through the pilot valve connects the chamber with the receptacle so the pressurized gases within the receptacle will enter the chamber to drive the piston and operate the valve when the pilot valve is opened. A counterbalancing means is provided to urge the outlet valve to closed position when the pilot valve is closed. A syphon tube or conduit connects the outlet valve with the bottom of the interior of the receptacle so that fire extinguishing medium will be discharged from the bottom of the receptacle and all of the fire extinguishing medium may be discharged from the receptacle, if desired, when the outlet valve is open.

Referring to the drawing in which there is shown a cross-sectional side view of a preferred embodiment of my invention, 1 denotes a receptacle containing a dry powder fire extinguishing medium 2 and a highly compressed propellant gas in the area 3. The dry powder fire extinguishing medium may be advantageously made of a mixture comprised substantially of bicarbonate of soda to which other ingredients to make the mixture moisture proof are added. However, any suitable mixture customarily used in dry powder fire extinguishers can be used. The propellant gas may be nitrogen, compressed air, carbon dioxide or any other gas which is capable of being highly compressed in order to propel the dry powder out of the container and will not support combustion.

An integral housing 4 is screwed into one end of the receptacle and encloses an outlet valve denoted generally by 5 and a pilot valve denoted generally by 6. One end

of the housing has a handle 7 by which the extinguisher may be easily carried.

The outlet valve 5 comprises generally a poppet-type valve 8 which is adapted to seat on valve seat 9. An engaging surface 18 of rubber, neoprene or other synthetic material may be superimposed upon the surface of valve 8 in order that an effective fluid tight seal will be made between it and seat 9. Valve 8 has a stem 10 which also serves as a piston rod connecting valve 8 with pneumatic piston 11 at its upper end. Pneumatic piston 11 is movable in a chamber 12 and may be advantageously provided with a washer 11a of rubber, neoprene or other suitable material in order that it will make a fluid tight seal with the sides of the chamber 12. The surface area of the piston 11 is made greater than that of the valve 8 so that the gas pressure in chamber 12 acting on the piston 11 will exert a greater force in a downward direction operating to open the valve 8 than in an upward direction to close the valve. A nozzle 13 fits into an aperture 14 made in the housing 4 which in turn connects with chamber 15 which is on the low pressure side of the valve 8. Nozzle 13 is so designed that it will disperse the fire extinguishing medium in a constant even pattern. The housing 4 is extended beyond the end of the nozzle 13 so that the nozzle protrudes into an aperture 16 in the housing. This extension will protect the tip of the nozzle from becoming damaged or bent. Aperture 16 may be internally threaded so a discharge hose may be screwed into the said aperture. When a discharge hose is used the dis-

persing nozzle 13 is positioned at the discharge end of the discharge hose. It is preferred to use such a discharge hose on the larger and heavier extinguishers so the discharging fire extinguishing medium may be directed upon the fire by merely directing the discharge hose and not the entire fire extinguisher.

A spring 17 continually urges the valve 8 to a closed position to aid in the function of valve 8 and to keep the valve from tending to open when the gas in the receptacle is at a low pressure due to the weight of the valve and thereby causing leakage. The spring 17 seats at one end on the outlet valve 8 and on the other end on an angular ring 19 which is threaded into the bottom of the housing 4. Angular ring 19 in turn has threaded into it a conduit or syphon tube 20 which extends to the bottom part of the container 1.

Pilot valve 6 comprises a fingertip control button 40 attached to a rod 41 which is adapted to engage the valve stem 42 of valve 43 when the button 40 is depressed. There is an indentation 70 on rod 41 positioned so it will be inside V-packing 49 when the pilot valve 6 is in closed position. Valve 43 seats on a valve seat 44 and is kept in a closed position by the pressure of the propelling gas on the bottom of the valve 43 and by means of a spring 45 which continually urges the valve 43 to a closed position. Valve 43 when closed separates chamber 12 from area 3. When valve 43 is open chamber 12 is connected to area 3 by means of passages 46, 47 and 48. The V-packing 49 provides a fluid tight seal between the rod 41 and the stem guiding plug 50 when pilot valve 6 is in open position and rod 41 is in depressed position so the indentation 70 is not inside V-packing 49. The valve 43, rod 41, and valve seat 44 are held in place inside of the housing 4 by means of an angular sleeve 51 which is threaded into the housing 4. A guard 52 prevents inadvertent operation of or tampering with the fingertip control button 40 and is adapted to be flicked to either side of the button 40.

I have found that the pilot valve 6 has a tendency to become clogged by the fire extinguishing powder when the pilot valve 6 is opened. This tendency is particularly pronounced after the extinguisher has been carried about so the fire extinguishing powder 2 has been shaken up.

A screen or filter 71 of cloth, fine metal mesh, or other suitable filter material may be advantageously provided at the beginning of passageway 47 to keep the fire extinguishing powder particles from entering passageway 47 and clogging the pilot valve 6.

Passage 47 extends into another passage 60 which in turn may be connected to a gauge, not shown in the drawing, adapted to indicate the gas pressure in the container. It may also accommodate a pressure release safety device which is not shown in the drawing.

Plug 61 is screwed in the end of the housing to seal chamber 12 and provide for assembly and repair of the valve parts. O seals 62, 63 and 64 provide a seal between adjacent parts to prevent gas leakage.

Operation

In order to operate the fire extinguisher, the handle 7 is grasped with one hand and the guard 52 is flicked to one side with the thumb. Fingertip control button 40 is depressed by the thumb to cause rod 41 to depress in turn valve stem 42. Before rod 41 was depressed the indentation 70 was positioned inside the V-packing 49, but when the rod 41 is depressed the indentation 70 passes completely below the V-packing 49 so the V-packing 49 will form a fluid tight seal between the guiding plug 50 and rod 41 to prevent the leakage of gas between the guide plug 50 and the rod 41 into the atmosphere. Since the cross-sectional area of the valve 43 is relatively small, little force will be necessary to depress the button 40 as the combined opposing forces of spring 45 and the propellant gas pressure will be relatively small. As the valve 43 is opened, gas from the area 3 of the container will pass through the passages 47, 46, around valve 43 into passage 48 and so into chamber 12. The pressure exerted upon piston 11 depresses it within chamber 12 and also piston rod 10 and valve 8. Valve 8 will therefore open, allowing the fire extinguishing medium 2 to be forced from the bottom of the container 1 through conduit 20, around the valve 8, through chamber 15 and out through dispersing nozzle 13. When fingertip control button 40 is released, valve 43 will close bringing rod 41 to upward position with the indentation 70 breaking the fluid tight seal between guide plug 50 and rod 41, thereby permitting the pressurized gas to escape from chamber 12, through passageway 48 and thence between guide plug 50 and rod 41 into the atmosphere. When the gas pressure is released from chamber 12, the gas pressure in area 3 and counter-balancing spring 17 will close valve 8 cutting off the flow of the fire extinguishing medium.

It is readily apparent that my invention provides an integral, portable, dry powder fire extinguisher which may be turned on and off without having to be completely exhausted in one operation, easily operated by fingertip control and carried and operated by one hand. When a discharge hose is screwed into the aperture 16 with a nozzle at the discharge end thereof the extinguisher may be held and operated by one hand and the end of the discharge hose held in the other hand to direct the discharging fire extinguishing medium onto the flame. Of course, it is understood that larger sizes of my fire extinguisher, too large to carry easily, can be provided with a suitable carrying cart to give them added portability.

While I have shown my extinguisher using a dry powder fire extinguishing medium, it is obvious that any pressurized fluid fire extinguishing medium could be used.

As various changes may be made in the form, construction and arrangements of the parts herein without departing from the spirit and scope of the invention and without sacrificing any of its advantages, it is to be understood that all matter herein is to be interpreted as illustrative and not in any limiting sense.

I claim:

1. In a fire extinguisher of the type having a receptacle

containing a fire extinguishing medium and charged with a pressurized fluid medium, an integral release valve means affixed to said receptacle and comprising a valve housing, an outlet valve for said extinguishing medium received in said housing and normally held in a closed position, a pneumatic piston connected to said outlet valve and adapted upon exposure to said pressurized medium to open said outlet valve, and manually operated pilot valve means for controlling the application of pressure to said piston; the improvement characterized by said pilot valve means comprising a valve rod slidably received in said housing and having a manually engageable portion projecting outwardly thereof, fluid passage means for exposing said piston to said pressurized fluid medium comprising a control valve near the inner end of said valve rod and a passage surrounding an intermediate portion of said valve rod, an annular sealing ring surrounding an outer portion of said valve rod and adapted to form a seal between said valve rod and housing, means normally maintaining said valve rod in an outer position in said housing, said valve rod having an indented portion adapted to lie adjacent said sealing ring when said valve rod is in said outer position whereby said sealing ring is ineffective to form a seal, said valve rod being adapted when moved inwardly of said housing to open said control valve.

2. The fire extinguisher of claim 1, further characterized by said fire extinguishing medium comprising a dry powdered material contained in the lower portion of the receptacle, the pressurized fluid medium being contained in the upper portion of the receptacle, said valve housing having a passage leading from said upper portion to said control valve, and said last mentioned passage having filter means therein to prevent said dry powdered material from flowing to said control valve.

3. In a fire extinguisher of the type having a receptacle containing a fire extinguishing medium and charged with a pressurized fluid medium, an integral release valve means affixed to said receptacle and comprising a valve housing, an outlet valve received in said housing and normally held in a closed position, and manually operated pilot valve means for opening and closing said outlet valve; the improvement characterized by said outlet valve having a surface exposed at all times to the interior of said receptacle and tending to maintain said outlet valve in a closed position, a piston received in said valve housing and connected to said outlet valve, said piston being adapted upon exposure to said pressurized medium to open said outlet valve, pilot valve means received in said valve housing and adapted when moved into a first position to expose said piston to the atmosphere and when moved into a second position to expose said piston to said fluid medium, and means normally maintaining said pilot valve means in said first position, said pilot valve means including a manually engageable portion exposed exteriorly of said valve housing and adapted to be manipulated to move said pilot valve means into said second position.

4. The fire extinguisher of claim 3, further characterized by said pilot valve means comprising a valve rod slidably received in said valve housing, sealing means near the outer end of said valve rod adapted to form a seal between said valve rod and valve housing, and means to render said seal ineffective when said pilot valve means is in said first position.

5. The fire extinguisher of claim 4, further characterized by said sealing means comprising an annular sealing ring surrounding said valve rod, and means providing a space between said valve rod and sealing ring when said pilot valve means is in said first position whereby fluid may flow through said space to the atmosphere.
